UNITED STATES PATENT OFFICE.

HENRY P. EASTON, JR., OF DENVER, COLORADO.

CLEANING AND ABRADING DEVICE.

Application filed March 15, 1924. Serial No. 699,484.

To all whom it may concern:

Be it known that I, HENRY P. EASTON, JR., a citizen of the United States, residing at Denver, in the county of Denver and State of Colorado, have invented certain new and useful Improvements in Cleaning and Abrading Devices, of which the following is a specification, reference being had to the accompanying drawings.

5 This invention relates to cleaning and abrading devices, and particularly to scouring pads for cleaning pots, pans and other culinary articles.

The general object of my invention is to 10 provide a pad of this character which consists of a backing of flexible material and a filling or facing of steel wool.

A further object is to provide a device of 15 this character which is flexible so that it may readily conform to the contour of a pot or pan whether that be concave or convex, and further to provide particularly effective means for holding the steel wool in place and preventing it from tearing away or 20 becoming loose with regard to the back.

A still further object is to provide a device of 25 this character with a handle portion at one end so that that portion of the mop coming in contact with the article does not have to be grasped.

Other objects will appear in the course 30 of the following description.

My invention is illustrated in the accompanying drawings, wherein:

35 Figure 1 is a perspective view of a scouring pad or cleaner constructed in accordance with my invention;

Figure 2 is a back view with the outer covering partially turned back;

40 Figure 3 is a section on the line 3—3 of Figure 1;

Figure 4 is a section on the line 4—4 of Figure 1.

Referring to these drawings, it will be 45 seen that my improved scouring pad comprises a backing 10, which is preferably of strong cloth. Upon the face of this backing is applied a facing 11 of steel wool or "Brillo" or like material. This steel wool 50 or Brillo does not extend entirely from one end to the other of the cloth but terminates short of one end of the cloth. The margins of the cloth back 10 may be turned inward over the margin of the steel wool, as at 12, 55 and held in place by stitching 13.

Preferably small strips of cloth, designated 14, extend longitudinally over the face of the steel wool and transversely thereof, these strips being stitched to the back 10 by 60 stitches 15 passing through the steel wool. Stitches of the same character pass through the inturned margins of the cloth so as to hold the steel wool firmly in place and prevent it from getting out of shape. The portion 16 constitutes a handle, as it may be 65 termed, whereby the scouring pad may be held without the hands of the worker coming in contact with that portion of the mop which is actually bearing against the kettle 70 or pot.

Preferably a thickness of cloth 17 will be disposed over the backing 10 so as to conceal the stitches. The steel wool may be stitched to the cloth either by wire stitching or by strong thread. There is a sufficient 75 padding of steel wool 11 that it will project some little distance beyond the face of the cloth backing where it is turned over upon the face of the steel wool and so that the scouring pad will last a considerable length 80 of time.

It will be obvious that this device is very 85 convenient, that it avoids the necessity of picking up small masses of steel wool between the fingers in order to scour pots and pans, and that with this device there is no necessity of the fingers coming in contact with the dirt or grease being removed from the pan or pot. Furthermore, inasmuch as it 90 is flexible it will conform to the curvature of the utensil and may be moved in any direction.

I do not wish to be limited to the exact 95 construction illustrated, as it is obvious that this construction might be changed in minor details and yet be within the scope of the appended claims.

I claim:

1. A scouring pad of the character described comprising a back of textile fabric 100 flexible in all directions, a mass of metallic wool applied to the back and stitched thereto at a plurality of points, one end of the back being extended to form a handle, and flexible strips extending longitudinally and 105 transversely over the face of the metallic wool and stitches extending through the flexible strips and metallic wool and holding the flexible strips to the back, the ends of the strips being stitched to the back. 110

2. A scouring pad of the character described comprising a back of textile material flexible in all directions, a mass of steel wool disposed against the face of the back and held thereto by stitching, a plurality of strips of flexible material attached at their ends to the back and extending over the steel wool and attached to the back by stitch-

ing passing through the flexible strips, the steel wool and the back, and a cover stitched 10 to the back and covering the stitching on the back.

In testimony whereof I hereunto affix my signature.

HENRY P. EASTON, JR.
